METHOD OF REDUCING OR REMOVING
WAVE CURL OR FRIZZINESS FROM HAIR

Edward Wheatley, West Wickham, England

Application July 4, 1939, Serial No. 282,800
In Great Britain July 26, 1938

5 Claims. (Cl. 132—31)

This invention relates to an improved method for removing or reducing superfluous curl, wave or frizziness from hair.

It is well known that to obtain a really satisfactory permanent wave the hair should be allowed to grow until the old wave has almost grown out; further, the possessors of naturally wavy or curly hair such as those of negroid or Semitic strain often desire to have the curl or frizziness removed or reduced from their hair as they find that such characteristics penalise them socially and in business.

The object therefore of the present invention is to provide a method of treating hair to remove wave, curl or frizziness therefrom consisting in chemically treating the hair to soften it and then passing the strands of hair lengthwise between rollers to apply a milling action whilst tensioning the strands by combing means, and then chemically treating the hair to re-harden it whereby hair with a curly, wavy, over permanent-waved or frizzy tendency or characteristic can be reduced to a straight or substantially straight condition.

In carrying out the method the appliance which is used in conjunction with substances for pre-treating and re-conditioning the hair comprises a frame supporting a plurality of teeth or pins and rotary rollers adapted to draw the hair through the interstices of the teeth or pins and simultaneously to apply rolling pressure to the hair, so that the pre-treated hair is milled by rollers.

In using the device the hair is pre-treated with a solution (which I term lotion A) so that it is softened or rendered malleable, the hair being rolled and stretched by the milling action of the rollers and the combining action of the teeth or pins whilst in such soft condition to remove the curl, wave or frizziness, the hair being subsequently treated with a reagent so that its normal hardness is restored.

The rolling and stretching reduces the hair to a straight or substantially straight condition. The hair is then treated with a further solution (which I term solution B) which neutralises the effect of the first solution, and hardens the hair in its straightened condition.

In order that this invention may be clearly understood and readily carried into effect a sheet of drawings is appended hereto illustrating a suitable appliance for effecting the rolling or milling and combing operations of the method of treating the hair in accordance with the present invention and wherein:

Fig. 1 is a side elevation view.

Fig. 2 is a rear elevation view.
Fig. 3 is a part sectional plan view, and
Fig. 4 is a sectional front elevation on line 4a—4a of Fig. 1.

Referring to the drawings the device illustrated is merely shown as an example of suitable means for effecting a combined milling and combing operation on the hair after the hair has been pre-treated and such appliance does not in itself comprise any part of the present invention which is primarily concerned with a method of treating hair. The said device comprises a two piece vice-like member or frame the upper and lower parts 1 and 2 respectively of which are hinged together along one edge as at 3, each frame member carrying one of a pair of rubber covered or other suitable rollers 4 and 5. Each roller is provided with a pinion or gear wheel (4a and 5a) and these two gear wheels mesh together when the frame is closed and are driven by a pinion 6 on the end of a small crank 7. The upper of the rollers is mounted in spring loaded bearings 8 and the pressure of the openings 9 thereof can be adjusted by raising or lowering the bearings 8 by the rotation of the milled nuts 10 on threaded pins 11 fixed at their lower ends in the bearings 8 and slidable through bushes 11a threaded into the ends of the upper frame member 1. Lock nuts 12 form abutments for the nuts 10.

The two frame members 1 and 2 are oblong plates, the upper plate 1 having an upwardly stepped front part 13 which accommodates the upper roller 4 so that the periphery of this upper roller projects very slightly below the plane of the base of the plate 1 to afford frictional driving contact with the lower roller 5. The bearing blocks 14 of this lower roller are accommodated within short vertical channels 15 in forwardly projecting end parts 16 of two side bars 2a of the base plate 2, set screws 17 locking the bearing blocks in position. These two side bars are bridged by an oblong base plate 2b which has a downwardly and rearwardly inclined upper surface upon which is detachably fixed by screws 18 a thin metal plate 19 carrying a plurality of staggered upstanding pins 20 forming in effect a plurality of parallel combs. The points of these pins nearly contact with the inner surface of the upper plate 1, such inner surface also being inclined so as to be parallel with the plate 19.

The plate 19 is formed along its rear edge with a trough 21 which is adapted to collect hair conditioning moisture with which the hair is pre-treated. The two frames 1 and 2 are secured

in the closed position by a hook catch 22 on one of the frames engaging over a pin 23 on the other frame. The springs 9 yieldingly oppose the pressing together of the two rollers so as to ensure a tight yet yielding grip of the rollers on the hair.

In carrying out the method comprising the present invention the hair is first thoroughly moistened with a solution which has a softening or plasticising effect on the hair structure, and the frame members of the before-mentioned device are swung apart and the roller engaged opposite sides of a tress of hair. The hair is then spread over the comb plate and the upper half of the device is then closed upon the hair and secured by the hook catch. Dependent upon the thickness of the tress of hair the bearings of the spring loaded roller can be adjusted and when arranged to the satisfaction of the operator who exercises discretion as to the permissible softening period, the hair is drawn through the appliance by rotating the crank handle so that the hair is drawn towards the head.

The combined rolling and combing whilst still in a soft and malleable condition straightens the hair and the softening or plasticising fluid is squeezed out by the rollers to flow into the aforesaid trough. This rolling action produces a milling operation on the hair.

A second fluid or preparation is then employed which has the effect of neutralising the remains of the first solution and re-hardening the hair to its normal degree of hardness in its straightened condition.

The rolling and stretching operation may be repeated if the hair still shows signs of too much curl or wave; this however must take place before using the second solution.

For convenience the two solutions may be called A and B, solution A being the plasticiser and solution B the neutraliser and hardener, it being understood that no claim is made for either of these solutions per se or their combination solely.

Solution A is an alkaline plasticising agent having a potash or sodium base and consists of measured quantities of:

Potassium or sodium hydroxide--ounces $\frac{1}{4}$ - $\frac{1}{2}$
Distilled water -----do----- 4
Essence of eau de Cologne or other suitable scent-----minims----- 1

The essence is optional, only being present to scent the substance. It is preferred to add to the above mixture about 2 drams of polyvinyl alcohol to form a gel to prevent the solution from flowing too freely.

This solution is employed in the manner described and causes the cellular structure of the treated hair to become plastic and malleable and the chemical action combined with the rolling and combing operation has the effect of slightly stretching the strands without destroying or impairing the cellular structure of the strands.

Solution B consists of measured quantities of:

Lig hamamelis (witch hazel)
Acetic acid
Industrial methylated spirit or spirits of wine
Essence of oil of geranium
Essence of oil of rosemary
Distilled water.

The ingredients are added in the sequence stated and the essence of oil of geranium or rosemary can be alternatives or combined.

Suitable proportions of the above constituents being as follows:

5 Lig hamamelis (witch hazel) -----ounces 1
Acetic acid -----do----- $\frac{1}{8}$ (or 2 drams)
Industrial methylated spirit or spirits of wine-----ounces 1
Essence of oil of geranium -----minims 1
10 Essence of oil of rosemary -----do----- 1
Distilled water-----ounces 2

This second solution is a neutraliser of the first solution and should be applied within ten minutes of the application of solution A. Its use has the effect of re-hardening the hair in its reformed condition. It is applied by sponging or swabbing it over the hair.

The perfume constituent in either solution may be varied as desired.

The hair should be shampooed after treatment with the second solution to wash away any traces of the chemicals.

I claim:

1. Method of treating hair to remove wave, curl or frizziness therefrom consisting in chemically treating the hair to soften it and then passing the strands of hair lengthwise between rollers to apply a milling action whilst tensioning the strands by combing means, and then chemically treating the hair to re-harden it.

2. A method of treating hair to remove wave, curl or frizziness therefrom comprising pre-treating the hair with a dilute caustic solution to soften the hair, traversing a pair of rotary rollers along the hair strands to mill them simultaneously with combing the hair to yieldingly oppose the drawing action of the rollers, and subsequently applying restorative to the hair to re-harden it.

3. A method of treating hair to remove wave, curl or frizziness therefrom comprising pre-treating the hair with a dilute caustic solution to soften the hair, traversing along the softened hair a combing device simultaneously with a pair of rotary rollers to tension and mill the hair, and subsequently applying a solution of witch hazel, acetic acid with an essential oil and a spirit to re-harden the hair.

4. A method of treating hair to remove wave, curl or frizziness therefrom comprising pre-treating the hair with a dilute caustic solution gelled by the addition of polyvinyl alcohol to soften the hair, traversing a pair of rotary rollers along the hair strands to mill them simultaneously with combing the hair to yieldingly oppose the drawing action of the rollers, and subsequently applying witch hazel and acetic acid combined with an essential oil and a spirit acting as a restorative to the hair to re-harden it.

5. A method of treating hair to remove wave, curl or frizziness therefrom comprising pre-treating the hair with a dilute caustic solution gelled by the addition of polyvinyl alcohol to soften the hair, traversing a pair of rotary rollers along the hair strands to mill them simultaneously with combing the hair to yieldingly oppose the drawing action of the rollers, and subsequently applying a mixture of witch hazel, acetic acid, industrial methylated spirit or spirits of wine, essence of oil of geranium or rosemary or their combination and distilled water acting as a restorative to the hair to re-harden it.
